TORQUE MEASURING WRENCH

Herman W. Zimmerman, North Chicago, Ill., assignor, by mesne assignments, to Frederick G. Wacker and Grace J. Wacker, Lake Forest, Ill.

Application January 28, 1937, Serial No. 122,839

20 Claims.

(CL 265—1)

My invention relates to wrenches and it has to do more particularly with wrenches of the class disclosed in United States Letters Patent No. 2,007,880, granted to John H. Sharp, on July 9, 1935, and which are adapted for measurement of the force or torque applied through the wrench in tightening or loosening bolts, studs, nuts, and the like.

One of the objects of my invention is to provide an improved wrench of the foregoing character, and which is of simple and sturdy construction, is inexpensive to manufacture, is so constructed that the parts thereof may be readily and easily assembled and disassembled, and which is adapted for the performance of its torque measuring function in a uniform and highly efficient manner.

Another object is to provide an inexpensive torque measuring wrench well suited for tightening and loosening various bolts, studs, nuts, etc., 20 used in connection with automotive and other engines, such, for example, as the cylinder head studs thereof, all of which should be tightened to the same extent to place them under a uniform tension to insure proper engine performance.

A further object is to provide a torque measuring wrench having spring members through which the force employed in tightening and loosening the bolts, nuts, etc., is applied, the arrangement 30 being such that the spring members are mounted in opposed relation independently of each other so that one spring member does not in any way affect the yieldable function of the other, and either of the spring members may be adjusted 35 without affecting the tension of the other spring member, whereby the spring members may be set to perform accurately under all load conditions.

Still another object is to provide a wrench of the foregoing character in which the spring members are arranged between a wrench handle and a rockable member having provision for engagement with a bolt, nut, stud, or the like, the arrangement being such that the rockable member is held normally in a neutral position independently of the pressure of either of the spring members and, as the rockable member is rocked in either direction, only one of the spring members is active at a time.

Additional objects are to provide a tension wrench that may be readily and easily handled by the operator and which is adapted to perform its functions properly and uniformly even in the hands of an unskilled operator; to provide a compact and balanced structure; to provide a wrench 55 of the foregoing character having a self-con-

tained and detachable indicating unit including adjustable indicating means so located as to facilitate observation thereof by the mechanic as well as to facilitate handling of the wrench; and to provide a wrench of the foregoing kind in which the rockable member and the spring members may be separately and independently assembled and disassembled without disturbing the position or condition of each other.

Other objects and advantages will become apparent as this description progresses, and by reference to the drawings, wherein,—

Figure 1 is a top plan view of one form of wrench structure embodying my invention;

Fig. 2 is a side elevational view of the forward portion of the wrench structure shown in Fig. 1;

Fig. 3 is a horizontal sectional view taken through the upper or indicator portion of the wrench, the same being taken substantially on line 3—3 of Fig. 4;

Fig. 4 is an enlarged vertical sectional view of the structure shown in Figs. 1 and 2;

Fig. 5 is a horizontal section taken substantially on line 5—5 of Fig. 4;

Fig. 6 is a section taken substantially on line 6—6 of Fig. 4; and

Fig. 7 is a section taken substantially on line 7—7 of Fig. 4.

The wrench shown in the drawings includes a head part 10 having an elongated handle 11 (Fig. 30 1) extending rearwardly therefrom. The forward end of the handle 11 is received within an opening 12 in the head 10 and it is secured therein in any suitable manner, as by the pin 13.

The forward end or nose of the head 10 takes 35 the form of spaced upper and lower shelf-like and parallel portions 14, 15 (Figs. 2 and 4) providing a rock space 10^a in which is received a part-circular, rockable member 16 which is adapted for operative connection with the work. The 40 member 16 is rockably supported in place in the following manner: The shelves 14 and 15 are provided with aligned screw-threaded openings 17, 18, in which are received threaded rings or bushings 19 and 20, respectively. The upper and 45 lower surfaces of the rock member 16 are provided with aligned grooves 21 in which annular tongues 22 on the inner ends of the bushings 19, 20 are received, the tongues 22 fitting into the grooves 21 in such a way that the member 16 is 50 permitted to take a free rotary rock movement without any material lateral or radial play or looseness. The outer ends of the bushings 19, 20 are provided with lateral flanges 23 which, when the bushings are screwed home within the

shelves 14, 15, seat firmly on the outer surfaces of these shelves, the flanges 23 serving as stops preventing the bushings 19, 20 from being screwed in so far as to tend to lock or cramp the rockable member 16. The bushing tongues 22 are of slightly less thickness than the threaded portion of the bushings, providing bushing shoulders 24 against which the upper and lower sides of the rockable member 16 seat when the bushings are screwed home, thereby preventing vertical play or looseness of the member 16 without hindering its free rockable action. With this arrangement, it will be seen that the member 16 is confined between the shelf-like portions 14, 15 for rock movement only. The bushings are locked in assembled position by screws 23^a carried by the wrench head 10, the arrangement being such that the heads of such screws seat in suitable recesses formed in the peripheral edges 20 of the bushing flanges 23.

The rockable member 16 is directly connected to the nut, bolt, stud or the like by detachable work engaging means which includes a rectangularly-shaped elongated adapter member 25 (Figs. 4 and 5) which is received in a similarly shaped and sized opening 26 provided in the member 16 at the rock center thereof. To detachably secure the adapter 25 in place, the member 16 is provided with a radially-disposed opening 28 leading from the outer rounded edge of such member into its opening 26, and the inner portion of this opening 28 is screw-threaded for reception of a set screw 27 which, when screwed into place, engages the adapter member 25 and locks the same in the desired position with respect to the member 16. The outer portion of the opening 28 (Fig. 5) is unthreaded and it is constructed and arranged to permit the free entry of the locking screw 27 to the threaded portion receiving the same. The outer end of the adapter 25 (Fig. 4) projects downwardly through and beyond the lower bushing 20 and is constructed to receive a socket 29 of selected size or other suitable coupling member (not shown) which is adapted to directly engage the bolt, stud, or the like.

In order to insure a free and smooth rock movement of the member 16 at all times, it may be desired to lubricate the bearing surface between such member and the bushings 19, 20. To that end, ports or openings 32 (Fig. 4) are provided in member 16 connecting the opening 28 with the grooves 21. Oil, or any other suitable lubricant, inserted in the opening 28 will readily find its way through the ports 32 into the grooves 21 and lubricate the bearing surfaces between the member 16 and the bushings 19, 20.

Rock movement of the member 16 in both directions is opposed by spring means, the extent of movement of the member 16 and the deflection of the spring means being measured to indicate the amount of torque or force applied through the wrench in tightening or loosening the stud, etc. This spring means will now be described. The wrench head 10, on the opposite sides of the handle 11, is provided with similar spring chambers 33, 34 (Fig. 5) which extend substantially parallel with the handle 11 on the opposite sides of the rock center of the member 16. Coil springs 35 and 36, preferably of identical kind, are mounted in the spring chambers 33, 34 and they are confined therein by screw-threaded plugs 37 screwed into the outer ends of the spring chambers 33, 34 and, preferably, locked in place therein by suitable pins 38. Each spring chamber 33, 34 is connected at its forward end to the space 10^a

between the shelf-like portions 14, 15 by reduced openings 39, 40, in which the stems of T-headed plungers 41 and 42 are slidably received. The heads 41^a and 42^a of these plungers are slidably received within the spring chambers 33, 34 and are constantly urged forwardly so that the T-heads 41^a and 42^a normally seat against the forward end wall of the spring chambers, the springs 35 and 36 being confined under the desired tension between the T-heads of the plungers and the 10 screw plugs 37.

The stems of the plungers 41 and 42 are of such length that when they are fully extended they project into the space 10^a between the shelf-like portions 14 and 15 far enough to engage arm-like portions 16^a, 16^b formed at the opposite sides of the rockable member 16. The arm-like portions 16^a, 16^b (Fig. 5) of the rock member 16 are substantially identical and they constitute the end parts of the part-circular portion of such member. The portions of these arms 16^a and 16^b which engage the plungers 41 and 42 are rounded to facilitate the rocking movement of the arms against the plungers and to minimize friction and wear therebetween. With this arrangement, the springs 35, 36 normally hold the plungers 41 and 42 fully extended with their head portions firmly seated against the forward ends of the spring chambers, and the plunger stems, due to the length thereof, merely contact the arms 16^a and 16^b of the rock member 16, holding the latter in a neutral position without exerting spring pressure upon either arm in either direction. In other words the plungers 41, 42 normally act merely as stops holding the member 16 in a neutral or at-rest position; and under conditions of use they serve as the means for operatively connecting the member 16 and the springs 35, 36. It will, therefore, be seen that either spring 35 or 36 may be adjusted independently of the other spring without affecting the position of the rock member 16 or without affecting the relation between the other spring and the rock member. The T-headed plungers insure this independent relationship. It will also be seen that when the wrench is applied to a bolt or nut and is moved in a clockwise direction, to tighten the same, resistance to this movement offered by the nut or bolt will be indicated by the extent of relative counterclockwise movements between the rock member 16 and the handle 11 as permitted by deflection of the spring 36. In other words, as soon as the resistance offered by the nut or bolt exceeds the resistance offered by the spring 36, continued movement of the handle 11 will result in compression of the spring 36 and the relative movement of the member 16, which compression and movement may be measured to determine the force or torque applied through the handle necessary to overcome the resistance offered by the nut or bolt. In the case of loosening the bolt, the handle 11 is moved in opposite or counterclockwise direction, at which time the spring 35 becomes effective in the accomplishment of the same relative action as described in connection with the tightening of the bolt. The structure so far described is so arranged that each spring 35 or 36 functions independently of the other so that variation in the tension of either spring will not affect the force resisting function of the other 70 spring.

In order that the operator may determine the amount of force or torque required to tighten or loosen any particular bolt or nut, I provide a self-contained indicating unit conveniently and 75

detachably located on the wrench head 10. Specifically, this indicating unit includes a casing 50 (Fig. 4) mounted upon the top of the wrench head and secured thereto by screws 51 passing therethrough and engaging suitable threaded openings in the upper wall of the wrench head. The rear under side of the casing 50 is provided with a pin 52 which engages a suitably provided opening 53 in the upper rear wall of the wrench head, which serves to properly position and align the casing 50 with the wrench head for a purpose which will become obvious hereinafter.

The casing 50 (Fig. 4) supports indicator mechanism which includes a dial 54 with suitable 15 graduations indicating, preferably, inch-pounds pressure. This dial is covered by a suitable, transparent cover 55 which may be formed of any suitable material. The dial 54 and cover 55 are located at the rear of the wrench head adjacent 20 the handle 11 where it may be more conveniently observed by the operator and where it is out of the way, so to speak, so that the operator may more readily grasp the wrench head for manipulating the wrench as a whole.

The indicator mechanism further includes a pointer 56 mounted above the dial 54 and carried by a member 57 projecting upwardly through the cover 54 and having an accessible knob portion 58. The member 57 is provided at its lower 30 end with a slightly tapered opening 59 in which the complementally shaped upper end of a shaft 60 is frictionally fitted. The fit between the shaft 60 and the opening 59 is such that the member 57 and shaft 60 normally rotate together but, 35 upon applying sufficient pressure rotatably to the knob 58 with the shaft 60 held stationary, the member 57 may be rotated relative to the shaft 60 to position the pointer 56 at any particular point with respect to the dial,—for example, the 40 zero point thereon.

The lower end of shaft 60 finds a bearing in an opening 61 (Figs. 4 and 7) in the lower part of the indicator casing, and this shaft fixedly supports a relatively small pinion 62 which is engaged with a longitudinally located rack 63. This 45 rack and the pinion 62 are confined in engagement with each other by a bracket member 64 having legs 64^a of a length substantially equal to the thickness of the pinion 62 and rack 63 and spaced apart a distance only slightly greater than the combined width of the rack and pinion. The bracket 64 is secured in place by screws 65 (Fig. 7) passing through the bracket legs 64^a and engaging suitably threaded openings in the bottom wall of the casing 50.

The indicator mechanism so far described is connected to the rockable member 16 through the rack 63 which extends forwardly from the pinion 62 where it engages another and larger pinion 66 fixed to a shaft 67. The upper end 68 of the shaft 67 is reduced and is rotatably supported in an opening 69 in the upper forward wall of the indicator casing. The pinion 66 and shaft 67 are normally supported in position, and the pinion 66 and rack 63 are normally held in engaging position, by a bracket 70 similar to the bracket 64. The legs 70^a of the bracket 70 are spaced apart sufficiently to accommodate the larger size pinion and the rack therebetween, and they are of a length substantially equal to the thickness of the gear 66 and rack so that these parts are confined normally as shown in Figs. 4 and 6. The bracket 70 is secured in position by screws passing through the legs 70^a thereof and engaging suitably threaded openings

in the adjacent upper wall of the indicator casing. To further insure smooth operation of the rack and pinion structure, the rack 63 is yieldably pressed into engagement with the pinions 62 and 66 by a spring 63^a having one end secured at 63^b to the casing 50 and its other end attached to the rack 63.

The lower end of the shaft 67 supports a clutch-like member 71 having a hub portion secured thereto by a pin 72. The clutch-like member 71 is provided with a lateral, annular flange 71^a, in which are mounted, diametrically opposed, depending pins 73 which are received in aligned openings 74 in the upper face of the rockable member 16.

It will be seen, from the foregoing, that upon tightening a bolt, stud or the like with this wrench, deflection of the spring 36 and resultant relative counter-clockwise movement of the rock member 16 will result in counterclockwise movement of the clutch-like member 71, the pinion 66, and like movement of the pointer 56 through the resulting movement of the rack 63 and pinion 62. Rock movement of the member 16 in an opposite direction, as when loosening a bolt, stud or the like, will result in the opposite movement of these parts and clockwise movement of the pointer 56. The relative sizes of the pinions 66 and 62 provide for a substantial movement of the pointer 56 upon a slight movement of the rock member. 30 The springs 35 and 36 are so constructed that a predetermined inch-pound pressure is required to deflect them to a predetermined extent, which deflection is indicated by the movement of the member 16. This deflection, although of slight extent, is readily registered in terms of inch-pounds through the rack and pinion structure described. 35

It will be clear from the foregoing that the purpose of my invention will be best served by first applying the wrench to the nut, stud or 40 the like, then setting the pointer 56 to the zero (or some other) mark on dial 54, and, if the bolt is being tightened, the operator may determine through the extent of movement of the pointer 56 the amount of inch-pounds pressure 45 or torque required to set up the stud or bolt to any desired extent. In this way, the operator may avoid breakage of the nut or bolt by avoiding the use of excessive pressure, as may happen in case the pressure applied exceeds the tensile 50 strength of the material of the stud or bolt. Also, the operator, in consecutively tightening a series of studs or bolts, as, for example, the cylinder head studs of an automotive engine, may initially set the wrench pointer to zero when 55 applying pressure to each stud and then set up each stud to the same predetermined extent. The same procedure may be employed, if the wrench is used for loosening studs, bolts or the like. For example, if the desired or predetermined 60 pressure has been exceeded in setting up the stud or bolt, the wrench may be actuated, without removing it from the stud to loosen the same to that point on the dial indicating the inch-pounds pressure required to further move such 65 stud or bolt.

It is believed that the objects and advantages of my invention as above first stated will be appreciated from the foregoing description. The wrench structure is of compact form and is balanced in such a way that it may be easily and readily handled by operators, skilled or otherwise. The construction is not only simple but sturdy, and it will serve its intended purpose indefinitely without repair and adjustment. It 75

is accurate in its indicating function. Accuracy at all times and under all weather conditions is insured. The parts may be readily and easily assembled and disassembled, as, for example, the rock member 16 may be readily assembled or disassembled without affecting the springs acting thereon, since the T-head plungers prevent the springs from affecting the normal at-rest position of the rock member when the handle 10 is at rest without pressure being exerted thereon.

It will be understood that, although I have shown only one form of structure embodying my invention, changes in details and arrangements of parts may be resorted to without departing from the spirit and scope of my invention as defined by the claims that follow.

I claim:

1. In a device of the class described, a wrench head, a handle extending from one end of said head, a member having opposed arm-like elements thereon mounted for rock movement at the other end of said head, coil spring members carried by said head and having their axes extending longitudinally of said handle in alignment with said arm-like elements, plunger members slidably carried by said head between said spring members and arm-like elements, means for limiting movement of said plungers forwardly under the influence of said springs to a predetermined point whereat said plungers merely abut said arm-like elements without exerting pressure on the latter, whereby said rock member in the inactive condition of the wrench is held in a predetermined balanced condition, work engaging means carried by said rock member on the rock center of the latter, and indicating means connected with said rock member registering the relative rock movement between the latter and said head and extent of compression of said spring members.

2. In a device of the class described, a wrench head having a pair of spaced, longitudinally extending and substantially parallel spring chambers formed therein and also having reduced slideways extending forwardly from said spring chambers, a handle on the rear end of said head, a rockable member mounted in the front end of said head and having a pair of opposed arm-like elements disposed in alignment with said slideways, springs mounted in said chambers in such a way as to be flexed axially of the latter, plunger members having a stem portion mounted in said slideways and another portion mounted in said spring chambers, said plungers being provided with shoulders adapted to engage said head at the end of said spring chambers adjacent said arm-like elements for limiting the extent to which said plunger members may be urged forwardly by said springs, said plunger stem portions being of sufficient length forwardly of said shoulders that when said shoulders engage said head said stem portions abut said arm-like elements without exerting pressure thereon, means carried by and located on the rock center of said rockable member and having provision for engaging said rock member with the work, and indicator means associated with said rockable member for registering the extent of relative rock movement between said head and rock member.

3. In structure of the class described, a wrench head having a rock space formed in its forward end, spaced, parallel and longitudinally extending spring chambers, and reduced slideways leading from said spring chambers to said space, a rock member mounted in said space and having

opposed arm-like elements aligned with said slideways, plungers having stem portions slidably mounted in said slideways and enlarged head portions slidably mounted in said spring chambers, springs mounted in said chambers and 5 engaging said plunger heads to normally urge said plungers forwardly with their heads seated against the forward ends of said spring chambers, said plunger stem portions being of such length when said plungers are urged fully forward that they merely abut said arm-like elements without exerting active pressure thereagainst providing a balanced support for said rock member when the wrench is inactive so that movement of said rock member in either 10 direction will merely compress the respective of said springs without affecting or being affected by the tension or position of the other spring, work adapter means mounted on the rock center of said rock member, and indicating means connected to said rock member for registering relative movement between said head and rock member.

4. In structure of the class described, a wrench head, a handle on one end of said head, a rock member on the other end of said head and having opposed arm-like elements thereon, spring members carried by said head in alignment with said arm-like elements, plunger members slidably carried by said head in alignment with said arm-like elements and normally serving as stops limiting said rock member to a neutral or non-pressure position, said plungers being operatively connected with said spring members whereby one of the latter is depressed by rocking said rock 35 member in either direction without affecting or being affected by the other spring member, work engaging means connected to said rock member in axial alignment with the rock center thereof, and indicating means connected to said rock 40 member and registering the extent of relative rock movement between the latter and said head and the extent of compression of the respective active spring member.

5. In structure of the class described, a wrench head having forwardly extending, spaced shelf-like portions having aligned threaded openings therein, a readily detachable rock member mounted between said shelf-like portions, said member having aligned annular grooves in its 50 opposite faces, threaded bushings mounted in said threaded openings and having tongues seated in the grooves of said rock member, work engaging means detachably carried by said rock member, means yieldably opposing movement of 55 said rock member, and indicating means connected to said rock member and registering rock movement of the latter.

6. In structure of the class described, a wrench head having its forward end shaped to provide a rock space with the opposed side walls thereof having threaded openings therein, a rock member mounted in said space and having aligned annular grooves in its opposite faces, means for mounting said rock member in said space including a pair of rink-like threaded bushing members mounted in said threaded openings and having extensions projecting into said rock member grooves, means for locking said bushings in 70 assembled position, work engaging means detachably carried by said rock member, said rock member being readily removable by detaching said bushings and said work engaging means, and means by which a lubricant may be supplied 75

through said rock member to the grooves therein without detachment of any parts.

7. In structure of the class described, a wrench head, a handle on one end thereof, a rock member on the other end thereof, spring means opposing rock movement of said member in either direction, and means for indicating the extent of movement of said rock member comprising a self-contained detachable unit including a casing, means for securing said casing to said head, a dial, a pointer, a clutch member detachably engaged with said rock member, and rack and pinion means between said clutch member and pointer transmitting motion of said rock member to said pointer.

8. In structure of the class described, a wrench head, a handle on one end thereof, a rock member on the other end thereof, spring means opposing rock movement of said member in either direction, and means for indicating the extent of movement of said rock member comprising a self-contained detachable unit including an elongated casing mounted upon and extending substantially throughout the length of said head, means detachably securing said casing to said head, a dial mounted in said casing adjacent said handle, a pointer rotatably movable with respect to said dial, a rotatable clutch member carried by said casing and projecting downwardly therefrom and operatively engaged with said rock member, and means for transmitting rotation of said clutch member to said pointer.

9. In structure of the class described, a wrench head, a handle on one end thereof, a rock member on the other end thereof, spring means opposing rock movement of said member in either direction, and means for indicating the extent of movement of said rock member comprising a self-contained detachable unit including a casing, means detachably securing said casing to said head, a dial in said casing, a pointer rotatable with respect to said dial, a support for said pointer, a clutch-like member positively connected to said rock member, connections between said clutch member and said pointer support for rotation of the latter as said rock member rocks, including a slip connection permitting said pointer support and pointer to be rotated independently of movement of said rock member whereby said pointer may be independently set to any predetermined position relative to said dial.

10. A torque measuring wrench comprising a head member, a handle on one end thereof, a rock member on the other end of said head member, spring means opposing rock movement of said rock member in either direction, and means for indicating the extent of movement of said rock member as opposed by said spring means to indicate the amount of force or torque applied through the wrench including a self-contained unit comprising a casing mounted on said head, a dial, a pointer movable with respect to the dial, a clutch member operatively associated with said rock member, and means between said clutch member and pointer for transmitting motion of said rock member to said pointer.

11. A torque measuring wrench comprising a head member, a handle on one end thereof, a rock member on the other end of said head member, spring means opposing rock movement of said rock member in either direction, and means for indicating the extent of movement of said rock member comprising a unit including an elongated casing portion extending substantially throughout the length of said head, a dial

mounted in said casing, at the end of said head member adjacent said handle, a pointer rotatably movable relative to said dial, a rotatable clutch member carried by said casing and projecting toward and into operative engagement with said rock member for movement therewith, and means for transmitting movement of said clutch member to said pointer.

12. A torque measuring wrench comprising a head member, a handle at one end thereof, a rock member at the other end of said head member, spring means opposing rock movement of said rock member in either direction, and means for indicating the extent of movement of said rock member comprising a unit including a casing, a dial in said casing, a pointer rotatable with respect to said dial, a support to which said pointer is fixedly secured, a clutch member positively connected to said rock member, connections between said clutch member and said pointer support for rotation of the latter as said rock member rocks, said connections including a rack and a slip connection between said rack and said pointer support, permitting the latter to be rotated independently of movement of said rock member when the latter is held stationary whereby said pointer may be independently set to any predetermined position relative to said dial.

13. A torque measuring wrench comprising a head member, handle means on one end thereof, a rock member pivotally supported at the other end of said head member and having an arm-like element thereon, a spring member carried by said head member in alignment with said arm-like element and yieldable in a direction substantially longitudinally of said handle means, a plunger member slidably carried by said head member in alignment with said arm-like element and provided with means positively limiting slide movement thereof toward said arm-like element, said plunger member being engaged by said spring member and constantly urged forwardly toward said arm-like element, work engaging means including a work adapter element carried by said rock member in axial alignment with the rock center thereof, and indicating means connected to said rock member and registering the extent of relative rock movement between the latter and said head and the extent of compression of the spring member as said rock member is moved in a direction to compress said spring member.

14. A torque measuring wrench comprising a head having a longitudinally extending spring chamber therein and also having a reduced slideway extending forwardly from said spring chamber, a rock member mounted for rock movement at the forward end of said head and having an arm-like element disposed in substantially axial alignment with said slideway, a spring member mounted in said chamber and adapted to flex in a direction axially of said slideway, a plunger member having a stem portion mounted in said slideway and a head portion mounted in said spring chamber, said plunger head limiting the extent of movement of said plunger forwardly through said slideway under the influence of said spring member, said plunger stem being of such length that in its fully extended position it abuts said arm-like element without exerting pressure thereon, work engaging means including a work adapter carried by said rock member on the rock center thereof, and indicating means operatively connected with said rockable member for regis- 75

tering the extent of relative rock movement between said rock member and head.

15. In structure of the class described, a wrench head provided with forwardly extending, spaced shelf-like portions having aligned openings therein, a detachable rock member mounted between said shelf-like portions, said member having aligned annular grooves in its opposite faces, guide members mounted in said openings and having inwardly extending tongues engaged in the grooves of said rock member for rotative support and guidance of the latter, means for detachably securing said guide members in said openings, work engaging means detachably carried by said rock member, means yieldably opposing movement of said rock member, and indicating means associated with said rock member for registering the extent of rock movement of the latter.
20. In structure of the class described, a wrench head having its forward end shaped to provide a rock space with the opposed side walls thereof having openings therein, a rock member mounted in said space and having aligned annular grooves in its opposite faces, means for mounting said rock member in said space including a pair of ring-like members mounted in said openings and having extensions projecting into said rock member grooves, means for securing said ring-like members in assembled position, work engaging means detachably carried by said rock member, said rock member being readily removable by detaching said ring-like members and said work engaging means, and means by which a lubricant may be applied through said rock member to the grooves therein without detachment of any parts.
25. 17. In structure of the class described, a wrench head, a rock member carried thereby, spring means opposing rock movement of said member, and means for indicating the extent of movement of said rock member comprising a self-contained detachable unit including a casing, means for securing said casing to said head, rotatable indicating structure, a clutch member detachably engaged with said rock member, and rack and pinion means between said clutch member and rotatable indicating structure for transmitting motion of said rock member to said structure.
30. 18. A torque measuring wrench comprising a head member, a rock member carried thereby, spring means opposing rock movement of said

rock member, and means for indicating the extent of movement of said rock member as opposed by said spring means to indicate the amount of force or torque applied through the wrench including a self-contained unit comprising a casing mounted on said head, a movable indicator supported by said casing, a clutch member operatively associated with said rock member, and means between said clutch member and indicator for transmitting motion of said rock member to said indicator.

19. In structure of the class described having a wrench head, a rock member carried by said head and spring means opposing relative rock movement between said head and rock member; means for indicating the extent of movement of said rock member in terms of pressure applied comprising a self-contained detachable unit including a support member, means for detachably securing said support member in a predetermined position upon said head, rotatable movement registering means carried by said support member, clutch means operably engaged with and movable with said rock member, said rock member and clutch means being so constructed and arranged that operative connection therebetween is effected merely by movement of said unit toward and upon said head at said predetermined position; and means between said clutch means and registering means for imparting motion to the latter as relative rock movement between said head and rock member takes place.

20. In a torque measuring wrench having a head rockably supporting a rock member and spring means opposing relative rock movement between said head and rock member; a pressure indicating unit for measuring the extent of relative rock movement of the head and rock member in terms of pressure applied which comprises a support member, means for detachably securing said support member in a predetermined position upon the head, rotatable means carried by said support member and indicating extent of relative movement of the head and rock member, means including a pin element carried by said support member and adapted to be operably associated with the rock member merely by movement of the indicating unit toward the latter, and means between said pin element and said registering means for imparting movement of said pin element to said registering means.
